UNITED STATES PATENT OFFICE

WILLIAM R. HUTTINGER, OF PHILADELPHIA, PENNSYLVANIA

ACTUATING AND CONTROLLING MECHANISM FOR ELECTRIC SWITCHES

Application filed May 15, 1929. Serial No. 383,899.

This invention relates to improvements in actuating and controlling apparatus for electric switches; and particularly to actuating and controlling apparatus for the 5 switches of high-tension circuits.

An object of the invention is to provide a controlling device adapted for use with a high-tension electric circuit such as a transmission line, and arranged so that the 10 simultaneous actuation of the regular switch for opening and closing the circuit and the ground switch can be effectively prevented; with the result that only one of these two switches can be operated at a time.

Another object of the invention is to provide a controlling device for a high-tension electric circuit which comprises securing 15 mechanism so mounted that either the ground switch or the regular switch is necessarily engaged and held against operation while the other switch is liberated when actuation thereof is desired.

A further object of the invention is to provide an operating means for the regular 20 switch of a high-tension electric circuit of such design that, when the switch is actuated, a predetermined degree of movement, which cannot be exceeded, is given to the parts by which the operation of the switch 25 is obtained. Thus damage to the switch or the parts by which it is mounted due to too much movement or too great an effort on the part of the operator, is averted.

Other objects and advantages of the invention are set forth in the following description and the novel features are pointed 30 out in the appended claims. The disclosure, however, is illustrative only and I may make changes which are not necessarily shown on 35 the drawings but, nevertheless, come within the principle of the invention as the claims define the same.

On said drawings:

Fig. 1 is a side elevation of a controlling 40 device according to my invention;

Fig. 2 is a top plan thereof; and

Fig. 3 is an end view seen from the left of Fig. 2.

On the drawings, the same numerals identify the same parts throughout.

The numeral 1 indicates a pair of vertical columns joined by beams 2 with reinforcing plates 3 at the ends of the latter to make a stronger connection between the beams 2 and columns 1. This structure may be part of the towers of a transmission line or a part of the framework at the point where the voltage is reduced for distribution to consumers. At 4 is a rod or link which connects with the ground switch (not shown) and the numeral 5 indicates a rotatable shaft which extends to the regular circuit switch. Both of these switches are located at some distance from the ground and are not illustrated, as they form no part of the invention; which resides in the operating and controlling apparatus for actuating these two switches. In all high-tension installations, the ground switch cannot be closed unless the circuit switch is opened, because if both are actuated together, serious damage would result. Hence, my controlling device is arranged so that it will lock one of these switches against movement while releasing the other. For this purpose, the controlling 50 device is provided with a detent member in the form of a slideable bar 6 mounted in bearings 7 on the columns 1 above the horizontal beam 2, and in the bearing 8 supported by this beam 2. This member 6 cooperates with elements for preventing movement of the link 4 and shaft 5 at the same time.

The link 4 is attached to a crank 9 on the shaft 10, which projects from the ends of a casing 11 secured to a plate 12, which is made fast to one of the columns 1 at the extremity of the member 6. The shaft 10 will carry a gear inside the casing 11 and this gear may be engaged by a worm 13 on the shaft 14 which can be turned by crank 15. Hence, rotation of the crank 15 by hand will turn the shaft 10 and raise or lower the connection 4. The shaft 10 projects from both sides of the casing 11 and on the side opposite the crank 9 this shaft carries a disk 16 having a perforation 17. Obviously, when the opening 17 is in line with the member 6 and this member is moved to the right so that its end penetrates

the opening 17, it will act like a lock bolt to prevent rotation of the shaft 10.

On the opposite extremity beyond the other columns 1, the member 6 carries an escapement wheel 18 mounted to turn on a stud or journal 19 fixed to the adjacent column 1. This escapement wheel may have a number of recesses 20 in its periphery, these recesses being seven in all. Below the escapement disk 18 is a shaft 22 carrying a fixed arm 23 bearing, at its outer end, an escapement pin 24 which enters the recesses 20. The shaft 22 carries a crank 21 at one extremity with the escapement arm 23 behind the crank and the shaft 22 passes through the column 1 and is supported in a suitable bearing on the beam 2 and carries an operating gear 25 to mesh with the gear 26 on the shaft 5. Hence, the turning of the crank 21 will rotate the shaft 5. The disk 18 will have an opening similar to the opening 17 for the adjacent end of the member 6. This member will be of such length that when it engages the disk 18, it will disengage the disk 16 and it must be moved to engage and stop one of these two disks before the other can be released and rotated. The member 6 carries a handle 27 so that it can be shifted by hand, and it may have collars 28 to receive between them the forked end of a lever 29 which may be operated from a convenient foot-pedal or other means for the same purpose.

Therefore, it is clear that if the ground switch is to be operated, the member 6 must first be shifted to lock the disk 18, thus freeing the disk 16, so that the crank 15 can be turned. If the regular circuit switch is to be closed, the member 6 must be shifted in the opposite direction to lock the disk 16 and release the disk 18. Then, the crank 21 can be turned to actuate the gear 25 and turn the shaft 5 through the gear 26.

In Figure 3, the disk 16 is free but the disk 18 is locked. To rotate the shaft 5, the disk 16 must be turned to aline the opening 17 and the bar 6. The bar is then shifted to carry its adjacent end into the opening 17, and its opposite end out of the opening in the disk 18 to free the latter. The ground switch is now open.

When the disk 18 is liberated to allow the crank 21 to rotate the shaft 5 to throw the circuit switch, this crank can be rotated as many times as there are notches 20 in the disk 18. That is to say, the crank can turn seven times and the escapement pin 24 will engage the notches 20 in succession to turn the disk 18. To do this, the crank 21 turns counterclockwise. At the end of the seventh revolution, however, the pin 24 will strike a point of the circumference of the disk 18 which is not recessed and then the crank 21, the shaft 22 and the shaft 5 can be turned no further but must stop and can only be

rotated in the opposite direction to reverse the shaft 5. This arrangement automatically limits the number of turns which can be given to the shaft 22 and the shaft 5 and prevents too great a movement being given to the parts which operate the circuit switch. In constructions of this sort, the shaft 5 is generally connected to a column of insulating elements placed one on top another in a well-known manner; the force being transmitted through the column, and if the shaft 5 were turned too much or too much force exerted, the column of superposed insulators would be considerably strained and damage might result. The presence of the disk 18 and escapement arm 23, however, obviates this risk and automatically stops further action as soon as the shaft 5 has been rotated to carry the switch parts into the desired position. Hence no damaging stresses can be put upon the switch or the connections for actuating it.

In order to lock the crank 21, when it has been turned through the regular switch connected to the shaft 5, the column 1 is provided with a pivoted yoke-shaped catch 31 mounted between a pair of perforated lugs 32 on the plate 33 affixed to the side of the adjacent column 1. At 34 is shown the pivot pin for the catch 31 and below this pin, the lugs 32 have openings for a padlock 35. Normally, the catch 31 will hang down between the lugs 32 out of engagement with the crank 21, but after the crank 21 has been moved to throw the circuit switch, the catch 31 will be lifted to engage the crank 21 on both sides; and then the padlock 35 can be put through the openings, holding the catch raised in operative position. The crank 21 cannot then be moved by any unauthorized person but will secure the parts in the desired position until the lock 35 through the openings is released and taken out. The catch 31 can of course secure the crank 21 at either end of its rotation. As will be apparent from Figure 3, the escapement disk 18 and arm 23 limit the motion of the crank 21 in both directions.

With this construction, it will be seen that not only is the simultaneous actuation of the two switches effectually prevented and the operation of these switches, one at a time, assured; but also injurious strains cannot be put upon the parts which actuate the circuit switch through the shaft 5. The turning of the crank 21 and shaft 22 beyond a given point are positively prevented, and the crank 21 can then be secured against being tampered with by unauthorized persons or accidentally manipulated to reverse the shafts 22 and 25 and actuate the circuit switch when operation thereof is not desired.

I claim:

1. An actuating and controlling device for a pair of switches comprising a connection for one of said switches, a crank for moving

5 said connection, a shaft carrying said crank, a disk on said shaft having an opening, a second shaft, an escapement disk connected to permit operation of said second shaft, said disk also having a perforation, and a bar slidably mounted between said disks and of such length that it cannot be withdrawn from the opening in one of said disks without entering the perforation in the other, the 10 bar thus preventing simultaneous movement of said disks.

15 2. An actuating and controlling device for a switch comprising a crank, an arm carrying an escapement pin on said crank, an escapement disk rotatably mounted adjacent said crank to limit the number of rotations of said crank and means cooperative with said escapement disk for preventing the rotation of said crank when it has reached a 20 predetermined position.

25 3. An actuating and controlling device for an electric switch comprising a crank, an arm on said crank bearing an escapement pin, and an escapement disk having recesses to cooperate with said arm, said recesses being located equal distances apart from the first to the last, and the first and last being separated by a greater interval to prevent continued rotation of the crank after the escapement 30 pin engages the last of said recesses in the rotation of said crank and said disk, and means cooperative with and adapted to engage said escapement disk to prevent rotation of said crank when it has reached a predetermined position.

40 4. An actuating and controlling device for a pair of switches comprising a connection for one of said switches, a crank for moving said connection, a shaft carrying said crank, a disk on said shaft having an opening, a second shaft for operating a second switch and provided with a crank, an arm on said last-mentioned crank carrying an escapement pin, an escapement disk having recesses 45 adapted to cooperate with said arm and said pin, said recesses being located equal distances apart from the first to the last, the first and last recesses being separated by a greater interval to prevent continued rotation of the second-mentioned crank after the escapement 50 pin engages the last of said recesses in the rotation of said second-mentioned crank and said escapement disk, said escapement disk also having a perforation, and a bar slidably mounted between said first disk and said escapement disk and of such length that it cannot be withdrawn from the opening in one of said disks without entering the perforation in the other, whereby simultaneous 55 movement of said first and second shafts is prevented.

60 WILLIAM R. HUTTINGER.
